TABLE

Lewis M. Greenway, Lansdowne, Pa.

Application May 25, 1935, Serial No. 23,494.

1 Claim. (Cl. 311—35)

The present invention relates to new and useful improvements in tables of the folding leg type and has for its primary object to provide, in a manner as hereinafter set forth, a table of this character embodying a top which may be readily reversed, thus permitting either side of said top to be used for any desired purposes, such as the playing of different games.

Other objects of the invention are to provide 10 a table of the aforementioned character which will be comparatively simple in construction, strong, durable, highly efficient and reliable in use, compact, light in weight, attractive in appearance and which may be manufactured at low 15 cost.

All of the foregoing and still further objects and advantages of the invention will become apparent from a study of the following specification, taken in connection with the accompanying drawings wherein like characters of reference 20 designate corresponding parts throughout the several views, and wherein:—

Figure 1 is a top plan view of a table constructed in accordance with the present invention, a portion of the top thereof being broken away to 25 disclose the interior of said top.

Figure 2 is a view in vertical transverse section through the table, taken substantially on the line 2—2 of Figure 1.

Figure 3 is a vertical sectional view through 30 a corner portion of the table, taken substantially on the line 3—3 of Figure 1.

Figure 4 is a view in vertical section through a corner portion of the table, showing the means 35 for securing removable ash trays in position.

Figure 5 is a detail view in vertical section, taken substantially on the line 5—5 of Figure 3.

Figure 6 is a vertical sectional view, taken substantially on the line 6—6 of Figure 1.

Figure 7 is a sectional perspective view of a 40 portion of the reversible top.

Figure 8 is a detail view in horizontal section and on an enlarged scale, showing the means for anchoring the rod on which the top pivots to the 45 stationary frame.

Referring now to the drawings in detail, it will be seen that the embodiment of the invention which has been illustrated comprises a frame 1, said frame being of any suitable material, 50 preferably wood. As illustrated to advantage in Figures 2 and 6 of the drawings, the frame 1 is of inverted U-shape in cross section. Secured in the corner portions of the frame 1 are braces 2. Referring now to Figure 3 of the drawings, it will 55 be seen that supporting legs 3 are hingedly

mounted, as at 4, on the braces 2. The legs 3 are adapted to swing or fold into portions of the frame 1, as indicated in dotted lines in Figure 3 of the drawings. When in unfolded position, the legs 3 bear against certain of the outer side walls 5 of portions of the frame 1. The legs 3 are releasably secured in unfolded position through the medium of slidable spring actuated bolts 5 which are engageable in sockets 6 provided therefor in said legs (see Figure 5). The bolts 10 5 are mounted in the frame 1.

Mounted in opposite sides of the frame 1 are aligned bushings 7, Figures 2 and 8. The reference numeral 8 designates generally a reversible top which is rotatably mounted in the frame 15 1. The reversible top 8 includes a frame 9 to the opposite sides of which panels 10 are secured, said panels 10 being parallel and provided, if desired, with covers 11 of suitable material. The frame 9 has formed therein channels 12 in which the marginal portions of the covers 11 are anchored through the medium of packing strips 13, Figure 6. A brace 14 traverses the frame 9 to 20 which the panels 10 are secured. The frame 9 further includes angle braces 15 at various points. 25

Mounted in the frame 9, at right angles to and extending through the brace 14 is a sleeve 16. The sleeve 16 is aligned with the bushings 7 and extending through said sleeve and into said bushings is a pivot rod 17 (see Figure 8) through 30 the medium of which the top 8 is rotatably mounted in the frame 1. Retaining nuts or caps 18 are threaded on the end portions of the rod 17, said retaining nuts or caps being provided with swinging handles or bails 19. It will be 35 observed that the retaining nuts or caps 18 are countersunk in the frame 1. Referring now to Figures 1 and 6 of the drawings, it will be seen that the top 8 is releasably secured against rotation through the medium of spring actuated bolts 20 which are slidably mounted in opposite sides of the frame 1 for engagement in sockets 21 which are provided therefor in the frame 9 of said top 8 at the ends of the brace 14. The bolts 20 are operable in housings 22 which 40 traverse opposite portions of the frame 1. The housings 22 enclose coil springs 23 which yieldingly urge the bolts 20 inwardly toward operative or locking position.

Removably mounted on the corner portions of 50 the frame 1 are ash trays 24. The ash trays 24 have formed therein grooves 25 (see Figures 3 and 4) for the reception of headed spring retracted pins 26 which are slidably mounted in the corner portions of the frame 1. 55

It is thought that the manner of using the table will be readily apparent from a consideration of the foregoing. The top 8 is normally secured against rotation in the frame 1 by the 5 bolts 20. When it is desired to reverse the top 8, the bolts 20 are withdrawn from the sockets 21 against the tension of the coil springs 23, thus freeing said top 8 for rotation on the rod 17. If desired, different games may be provided on the 10 opposite sides of the reversible top 8. To swing the legs 3 to folded position within the frame 1, the bolts 5 are, of course, disengaged from the sockets 6. Any suitable means may be provided, if necessary or desired, for releasably securing 15 the legs 3 in folded position.

It is believed that the many advantages of a table constructed in accordance with the present invention will be readily understood, and although a preferred embodiment of the invention

is as illustrated and described, it is to be understood that changes in the details of construction and in the combination and arrangement of parts may be resorted to which will fall within the scope of the invention as claimed. 5

What is claimed is:—

In a table and in combination, an open frame, a reversible top swingable in the open frame, aligned bushings disposed in opposite portions of the frame with their inner ends flush with the inner sides of said frame portions, a sleeve disposed in the reversible top in alignment with and abutting at its ends against said bushings, a rod extending through said bushings and sleeve and having threaded ends and nuts disposed in 10 the outer sides of said opposite frame portions and on the threaded ends of the rods and abutting the outer ends of the bushings. 15

LEWIS M. GREENWAY.
